UNITED STATES PATENT OFFICE

2,536,908

SAVAGE BOAT

Ernest Francis Chadwick, Marysville, Wash.

Application April 7, 1947, Serial No. 739,752

2 Claims. (Cl. 114—0.5)

1

This invention relates generally to towboats and other vessels, and more particularly to a boat used for salvage purposes, the device comprising a combination with such a boat of a tube extending substantially vertically through one end of a boat with a spud slidably mounted within this tube and having a fair lead on the upper portion of the spud, the fair lead guiding a cable, one end of which cable will be secured to the material to be salvaged from the shore, the other end of the cable being wound on a reel on the deck of the boat, whereby the spud is forced downwardly through the tube and provides temporary anchoring of the boat during the salvage operation, the invention including a second cable securable to the lower end of the spud whereby the spud may be conveniently raised when the salvaging operation is completed.

A primary object of this invention is to provide a device of the character mentioned, in which the component parts are constructed with extreme simplicity, susceptible of manufacture in very rugged form, and generally adapted for selective replacement, when required.

Another object of this invention is to provide means whereby a salvage boat may be expeditiously anchored and operated with a minimum of equipment, and to further provide means whereby the anchoring means may be easily retracted, when it is desired to move the boat to a new location.

Another object of this invention is to provide means of this character in which the controls of the anchor and the dragline are grouped together at one point on the deck of the boat.

And a last object to be specifically mentioned is to provide means of this character which is relatively inexpensive and practicable to manufacture, extremely simple and conveniently used under various conditions, and which will give generally efficient and durable service.

With these objects definitely in view, this invention resides in certain novel features of construction, combination and arrangement of parts and portions as will be hereinafter described in detail, particularly set forth in the appended claims, and illustrated in the accompanying drawings which form a material part of this application, and in which:

Figure 1 is a side elevational view of a salvage boat with this invention incorporated thereon, the view including the portion of the shore line and a log which is being salvaged;

Figure 2 is a fragmentary view of the portion

of the structure shown in Figure 1, the portion of the boat being broken away to show the underlying structure in vertical section;

Figure 3 is a view similar to Figure 2 but showing the spud retracted;

Figure 4 is an enlarged detailed view of the spud, reel and contiguous structure, the tube wherein the spud is housed being shown in vertical section, the spud and tube being broken, to conserve space; and

Figure 5 is an enlarged top plan view of the spud, reel and adjacent structure.

Similar characters of reference designate similar or identical parts and portions throughout the specification and throughout the several views of the drawings.

Referring now to the drawings in detail, the environment wherewith this invention is adapted to be used includes a log 10, used to represent the object on the shore 12 which it is desired to salvage. A boat, generally represented at 14, may be of any desired type and will include a deck 16 and a hull portion 18. This invention may be incorporated with either the front or bow portion of the boat or another portion of the boat, there being provided in every case a tube 20 which will be disposed in substantially vertical position and will extend to said deck and hull portion. This tube 20 will preferably have an integral flange 22 on the lower end thereof and the upper end of the tube will be provided with a flange 24.

A spud 26, preferably sharpened at the lower end 28, is slidably mounted within the tube 20, and the upper end of this spud is provided with a fair lead 30 of any suitable type.

A double reel comprising the single reel 32 and the single reel 34 is operatively mounted on the deck 16. A base plate 36 for this reel assembly is formed with a projecting portion 38. The reels 32 and 34 are co-axially mounted, a large center bearing 40 comprising the main supporting member for both reels, the crank handle 42 being directly connected with the reel 32, and the crank handle 44 being connected by means of the shaft 46, pulleys 48 and 50, a belt 52 entrained on these pulleys, to drive the reel 34 which is directly secured to the shaft 54 on which the pulley 50 is mounted. The exact construction of this reel is immaterial in the present disclosure, but such reel assembly will normally include collars 56 to retain the reels in position on the shafts 58 and 54, bearings 60 for the shaft 46, and the necessary complement of equipment to properly secure the reel assembly to the deck 16 and provide for the

selective actuation of the reels 32 and 34 by the hand cranks 42 and 44, respectively.

A cable 62 is terminally secured to the reel 34 and is guided by the vertical rolls 64 and 66, and a horizontal roll 68, to enter the top of the tube 32 the other end of this cable 62 being secured, as at 70 to the spud 26 adjacent the lower end 28 thereof. It will be understood that the tube 20 is of a diameter considerably in excess of the diameter of the spud 26 and that the spud and cable 62 may freely slide within the tube. The rolls 64 and 66 will ordinarily be secured by their vertical shafts 72, to the deck 16, and the roll 68 is shown secured to the top flange 24 of the tube 20, by means of terminal bearings 74.

The shore line 76 is terminally secured to the reel 32 and is threaded through the fair leads 30, to extend shoreward for securement to the material to be salvaged, suitable grappling or attaching means being provided on the terminal of said cable, to facilitate the securement of the salvage material. The fair leads 30 may comprise a horizontal roller 78 and a pair of vertical rollers 80, and it will be understood that suitable plate attachment means 82 will be provided on the upper end of the spud 26.

The operation of this invention will be clearly understood from the foregoing description of the mechanical details thereof, taken in connection with the above recitation of the objects sought to be achieved by this invention, but it may be expedient to further illustrate the operation of this invention by reference to the use thereof in salvaging logs set adrift from booms during transportation of these log booms along river and coastal routes. These logs are, of course, of considerable value and a salvage boat of the general character illustrated in Figure 1 is used to salvage those logs after the same have become beached and the work is expedited and facilitated by the use of this invention. The boat is made to approach reasonably close to the shore and the hand crank 44 is turned to allow the reel 34 to unwind the cable 62 and thus allow the spud 26 to gravitate downwardly through the tube 20 until the lower end 28 of the spud contacts a submarine portion of the shore 12, all as indicated in Figure 1. One end of the shore line 76 is thrown ashore and secured to the log 18 and the hand crank 42 is used to wind the reel 32 and the cable 76 is tensioned, this action causing the spud 26 to be forced more deeply into the material of the beach, more securely anchoring the boat, and completely preventing the boat from being drawn shoreward when sufficient tension is placed on the shore line 76 to draw the log 18 away from the shore and eventually on to the deck 16 or into a boom of salvage logs. If no other logs are to be salvaged in the immediate vicinity, the reel 34 is actuated in the opposite direction to tension the cable 62 and to retract upwardly the spud 26, and when the spud has been sufficient-

ly released the boat is once again free to be maneuvered into a new position.

It should be clearly understood that the exact construction and proportionment of the various elements of this invention, as for example the positioning and form of the rollers 64 and 66, the fair lead 30, and the particular mechanical combination of the reels 32 and 34, is described in this application with a view to illustrating rather than limiting the particular construction by which this invention may be reduced to practice. Therefore, though there has been shown a particular embodiment of this invention, this application is not limited to this particular embodiment, but it is desired to include in the scope of this invention the construction, combination and arrangement of parts and portions substantially as set forth in the appended claims.

What is claimed as new and desired to be secured by Letters Patent is:

1. In combination in a salvaging boat, a tube extending substantially vertically through one end of a boat, a spud slidably mounted within said tube, a fair lead on the upper portion of said spud, a reel operatively mounted on said boat beneath the level of said fair lead, and a shore line threaded through said fair lead and terminally connected to said reel, whereby the spud is forced downwardly when the shore line is terminally secured as to a beached log and the reel operated.

2. In combination with a boat, a tube extending substantially vertically through one end of a boat, a spud slidably mounted within said tube, a fair lead on the upper portion of said spud, a reel operatively mounted on said boat beneath the level of said fair lead, a shore line threaded through said fair lead and terminally connected to said reel, whereby the spud is forced downwardly when the shore line is secured ashore and the reel actuated, and a second cable secured to said spud adjacent the lower end thereof and extending upwardly through said tube, whereby the spud may be raised.

ERNEST FRANCIS CHADWICK.
